UNITED STATES PATENT OFFICE.

FREDERICK G. SARGENT, OF WESTFORD, MASSACHUSETTS, ASSIGNOR TO C. G. SARGENT'S SONS CORPORATION, OF GRANITEVILLE, MASSACHUSETTS, A CORPORATION OF MASSACHUSETTS.

WOOL-WASHER.

973,388.

Specification of Letters Patent. Patented Oct. 18, 1910.

Application filed January 20, 1910. Serial No. 539,170.

To all whom it may concern:

Be it known that I, FREDERICK G. SARGENT, a citizen of the United States, residing at Westford, in the county of Middlesex and 5 State of Massachusetts, have invented a new and useful Wool-Washer, of which the following is a specification.

This invention relates to improvements in a well known type of wool washing machine. 10 The principal objects of the invention are to provide an improved circulation of the water in the tank whereby it can be used over and over to a certain extent, and whereby it can be heated in an economical and 15 convenient manner; and also to an improved settling device for the water.

Further objects and advantages of the invention will appear hereinafter.

Reference is to be had to the accompanying drawings in which—

Figure 1 is a plan of a well known type of wool washer with a preferred embodiment of the invention applied thereto; Fig. 2 is a sectional view of the same on the line 25 2—2 of Fig. 1, and Fig. 3 is a sectional view of a portion of the water circulating device.

In these drawings the tank or bowl 20 is shown as provided with a screen or support 21 for the wool, but the internal mechanism 30 is not shown.

The water which circulates through the tank passes out through an overflow pipe 25 into a settling tank 26 arranged parallel with the washing bowl and at the rear thereof. 35 In the bottom of the settling tank are a series of depressions 27 separated by partitions 28 extending part way to the top of the settling tank. The depressions have at the bottom closures 29 by which they may be 40 emptied as is the case with washing bowls as now constructed. Extending down from the top of the settling tank are a plurality of partitions 30 depending to a point below the tops of the partitions 28, so that as the 45 water flows along the settling tank as indicated by the arrows in Fig. 2, that at the bottom of the settling tank will remain qui-

escent and settle, and yet suspended particles attempting to flow along, as well as floating particles, will necessarily be submerged in each of the depressed bottoms. 50 This provides for efficient settling of the liquid.

The water flows out of the settling tank into the end of the washing bowl through a 55 pipe 31. In order to force the water through the pipe 31, and especially to heat it on the way, a steam injector nozzle 33 is introduced into the pipe 31. As the water already is heated it will be seen that less steam is required than is the case ordinarily, also great 60 saving is effected in the amount of water used.

While I have illustrated and described a preferred embodiment of the invention, I 65 am aware that many modifications can be made therein by any person skilled in the art without departing from the scope of the invention as expressed in the claim. Therefore, I do not wish to be limited to all the 70 details of construction herein shown and described, but

What I do claim is:—

In a wool washer, the combination of a 75 washing bowl having means for supporting wool therein and adapted to receive settling from the water in the bottom thereof, an outlet pipe at one end, an inlet pipe at the other, a settling tank arranged longitudinally with respect to said bowl and at the 80 rear side thereof and extending from one end thereof to the other, said outlet pipe discharging directly into one end of said settling tank, and means for drawing the water from the other end of the settling tank, heating it, and introducing it directly into the 85 washing bowl.

In testimony whereof I have hereunto set my hand, in the presence of two subscribing witnesses.

FREDERICK G. SARGENT.
